UNITED STATES PATENT OFFICE.

JAMES J. McCARTHY, OF CHICAGO, ILLINOIS.

CAR-ROOF.

1,005,262.

Specification of Letters Patent. Patented Oct. 10, 1911.

Application filed April 29, 1909. Serial No. 493,043.

To all whom it may concern:

Be it known that I, JAMES J. McCARTHY, a citizen of the United States, residing at Chicago, in the county of Cook and State 5 of Illinois, have invented certain new and useful Improvements in Car-Roofs, of which the following is a specification, reference being had to the accompanying drawings.

10 My invention relates to car roofs, and has to do particularly with roofs in which a sheet-metal roof is employed underneath an outer wooden roof.

It has for its object to provide certain 15 improvements in the construction of the roofing-sheets and their arrangement in connection with the other parts of the roof. I accomplish this object as illustrated in the drawings and as hereinafter described.

20 What I regard as new is set forth in the claims.

In the drawings,—Figure 1 is a partial cross-section of a freight-car showing my improvements; Fig. 2 is a perspective view 25 of a part thereof; Fig. 3 is a plan view of a part of one of the roofing-sheets, showing the outer end thereof, and Fig. 4 is a perspective view of the upper end of one of the joint strips.

30 Referring to the drawings,—4 indicates the car, of which 5 is one of the carlines, 6 the ridgepole, and 7—8 the usual side-plates.

9 indicates the siding, and 10—11 the lower 35 and upper purlins.

12 indicates the wooden roof, which is composed of boards secured upon the upper purlins 11 and ridgepole 6.

13 indicates the roofing-sheets, the construction of which is best shown in Figs. 40 2 and 3. As therein shown, each of the sheets is provided at one edge with an inverted U-shaped flange 14 and at the other edge with an upturned flange 15, which fits 45 within the U-shaped flange 14 of the adjacent edge, thus forming an interlocking joint which is protected from moisture but which does not interfere with the movement 50 of the roofing-sheets in adapting themselves to the strains of the car. The lower or outer corners of the roofing-sheets are cut away, as shown at 16 in Figs. 2 and 3, so as not to interfere with the nailing of the joint-strips to the side-plates, as here- 55 inafters described. At their inner ends the

roofing-sheets are provided with upturned flanges 17. The inner ends of the roofing-sheets are fitted into recesses 18 at the sides of the ridgepole so that they are protected from moisture by the overlying portion of 60 the ridgepole, as shown in Fig. 1. The roofing-plates are supported intermediately by the purlins 10 and at their outer ends by the side-plates 7. They project slightly beyond the siding 9, as shown in Fig. 1, so 65 that any water which falls upon the roofing-sheets is discharged at the sides of the car.

19 indicates joint-strips in the form of wooden strips, which extend transversely of the car over the joints connecting the side 70 edges of the roofing-sheets, said joint-strips having grooves 20 on their under surfaces which overlie the joints, as best shown in Fig. 2. At their inner ends the corners of the joint-strips are cut away, as shown at 75 21—22 in Fig. 2, to receive the flanges 17 of the roofing-sheets and provide sufficient space so that the movement of the roofing-sheets under the wrenching strains of the car is not interfered with. At the same time 80 through the engagement of the flanges 17 with the inner ends of the joint-strips excessive outward movement of the roofing-sheets is prevented. By cutting away the corners of the inner or upper ends of the 85 joint-strips as above described I form a tongue 19^a which projects beyond the flanges 17 of the roofing sheets and abuts against the ridgepole so that the joint-strips are thus held rigidly against longitudinal movement 90

without preventing such inward movement of the roofing-sheets as may be necessary as to allow them to accommodate themselves to the wrenching strains to which the roof is subjected. At their outer ends the joint-strips 95 19 are secured by nails or screws 23, which connect them with the side-plates 7—8. Said nails do not pass through the roofing-sheets, but through the spaces 16 formed by cutting away the corners of the sheets, as shown in Fig. 2. The joint-strips 19 extend out beyond the outer ends of the roofing-sheets, as shown in Fig. 1, and serve to hold the outer ends of the roofing-sheets down, thus making it unnecessary to employ clips or 100 blocks for that purpose. 24 indicates the fascia-boards which abut against the outer ends of the joint-strips 19 and are secured to the side-plates 7—8, preferably by bolts 25, as shown in Fig. 1. The outer ends of the 105 110

roofing-boards 12 project over and are secured to the upper edges of the fascia-boards.

What I claim as my invention, and desire 5 to secure by Letters Patent, is,—

1. In a car-roof, the combination with suitable supporting devices, of a plurality of roofing-sheets joined together at their side edges, side-plates supporting the outer or 10 eave ends of the roofing-sheets, the corners of the roofing-sheets overlying the side-plates being cut away, joint-strips overlying the side edges of the roofing-sheets and the cut away corner portions thereof, and means 15 securing said joint-strips to the side-plates at the spaces formed by cutting away the corners of the roofing-sheets.
2. In a car-roof, the combination with suitable supporting devices, of a plurality of 20 roofing-sheets joined together at their side edges, side-plates supporting the outer or eaves ends of the roofing-sheets, the corners of the roofing-sheets overlying the side-plates being cut away, joint-strips overlying 25 the side edges of the roofing-sheets and the cut away corner portions thereof, and nails securing the joint-strips to the side-plates and passing through the spaces formed by 30 cutting away the corners of the roofing-sheets.
3. In a car-roof, the combination of a ridgepole having recesses at its sides, side-plates, roofing-sheets having upturned 35 flanges at their side and ridge edges, the side edges of adjacent sheets being connected together, and the corners of the roofing-sheets overlying the side-plates being cut away, joint-strips having grooves on their under

sides adapted to receive the side flanges of the roofing-sheets, the inner ends of said joint-strips projecting beyond the ridge flanges of the roofing-sheets and being fitted in the grooves of the ridgepole, and means 40 securing the joint-strips to the side-plates and passing through the spaces formed by 45 cutting away the corners of the roofing-sheets.

4. In a car-roof, the combination of suitable supporting devices comprising side-plates at the sides of the car, roofing-sheets 50 supported at their eave ends by said side-plates, said sheets having cut away portions overlying the side-plates, and joint-strips overlying the joined edges of adjacent plates and such cut away portions, and 55 fastening devices passing through such cut away portions of the sheets for securing the joint-strips to the side-plates.

5. In a car-roof, the combination of a ridgepole having recesses at its sides, side-plates, roofing-sheets having up-turned 60 flanges at their sides and ridge edges, the side edges of adjacent sheets having interlocking engagement with each other, and joint-strips having grooves on their under 65 sides to receive the side flanges of the roofing-sheets, the upper ends of said joint-strips having tongues which project between the ridge flanges of the adjacent 70 roofing sheets and being fitted in the recesses in the ridgepole.

JAMES J. McCARTHY.
